CLAIM

The ornamental design for a gymnasium insert for a playpen, as shown and described.

DESCRIPTION

FIG. 1 is a perspective view of a gymnasium insert for a playpen showing my new design;

FIG. 2 is an end elevational view thereof, the opposite end being a mirror image thereof;

FIG. 3 is a side elevational view thereof, the opposite side being a mirror image thereof; and,

FIG. 4 is a top plan view thereof.

The broken line showing of a playpen in FIG. 1 is for illustrative purposes only and forms no part of the claimed design.

FIG. 1

FIG. 2

FIG. 3

FIG. 4
